UNITED STATES PATENT OFFICE

150,087

DESIGN FOR A LUGGAGE CARRIER FOR AN
AUTOMOBILE

William E. Martin, Kewanee, Ill.

Application July 16, 1946, Serial No. 131,608

Term of patent 14 years

(Cl. D14—27)

To all whom it may concern:

Be it known that I, William E. Martin, a citizen of the United States, residing at Kewanee, in the county of Henry and State of Illinois, have invented a new, original, and ornamental Design for a Luggage Carrier for an Automobile, of which the following is a specification, reference being made to the accompanying drawing, forming a part thereof.

In the drawings,

Fig. 1 is a side elevational view of a luggage carrier for an automobile, showing my new design; and

Fig. 2 is a rear elevational view thereof.

The dotted line showing of an automobile in the drawing figures is for illustrative purposes only.

I claim:

The ornamental design for a luggage carrier for an automobile, substantially as shown and described.

WILLIAM E. MARTIN.
